[54] COMBINED FURNITURE PULL AND ESCUTCHEON

Schlage Builder's Hardware, Cat. C-50 9/1951, p. CD-30, 'Monarch' knob and rose.

[75] Inventor: **Emil J. Bocade**, 135 Lemyra, SE., Wyoming, Mich. 49508

Primary Examiner—Wallace R. Burke
Assistant Examiner—B. J. Bullock
Attorney, Agent, or Firm—Peter P. Price

[73] Assignee: **Keeler Corporation**, Grand Rapids, Mich.

[57] **CLAIM**

The ornamental design for a combined furniture pull and escutcheon, substantially as shown and described.

DESCRIPTION

FIG. 1 is a perspective view of a combined furniture pull and escutcheon showing my new design;
FIG. 2 is a front elevational view of FIG. 1;
FIG. 3 is a side elevational view of FIG. 1;
FIG. 4 is a rear elevational view of FIG. 1;
FIG. 5 is a perspective view of a second embodiment of the design of FIG. 1;

FIG. 6 is a front elevational view of FIG. 5;
FIG. 7 is a side elevational view of FIG. 5;
FIG. 8 is a rear elevational view of FIG. 5;
FIG. 9 is a perspective view of a third embodiment of the design of FIG. 1;
FIG. 10 is a front elevational view of FIG. 9;
FIG. 11 is a side elevational view of FIG. 9;
FIG. 12 is a rear elevational view of FIG. 9;
FIG. 13 is a perspective view of a fourth embodiment of the design of FIG. 1;
FIG. 14 is a front elevational view of FIG. 13;
FIG. 15 is a side elevational view of FIG. 13;
FIG. 16 is a rear elevational view of FIG. 13;
FIG. 17 is a perspective view of a fifth embodiment of the design of FIG. 1;
FIG. 18 is a front elevational view of FIG. 17;
FIG. 19 is a side elevational view of FIG. 17;
FIG. 20 is a rear elevational view of FIG. 17.
